UNITED STATES PATENT OFFICE.

JOSEPH B. RODGER, OF BATAVIA, ILLINOIS, ASSIGNOR TO THE CHALLENGE WINDMILL AND FEED MILL COMPANY, OF SAME PLACE.

VAPOR-ENGINE.

SPECIFICATION forming part of Letters Patent No. 661,078, dated November 6, 1900.

Application filed May 1, 1899. Serial No. 716,150. (No model.)

To all whom it may concern:

Be it known that I, JOSEPH B. RODGER, a citizen of the United States, residing in Batavia, in the county of Kane and State of Illinois, have invented a new and useful Improvement in Vapor-Engines, of which the following is a specification.

This invention relates to gasolene-engines, and my endeavor therein has been to improve the construction thereof in the features hereinafter set forth, and particularly pointed out in the claims, the nature of the invention being fully disclosed in the description given below and also in the accompanying drawings, in which—

Figure 1 is a side elevation, Fig. 2 a plan, and Fig. 3 an elevation of the side opposite to that shown at Fig. 1, of my improved engine. Fig. 4 is an end elevation. Fig. 5 is a section on the line 8 8 of Fig. 2, and Figs. 6 and 7 are details of the governor.

My improved engine belongs to that type of engines in which an ignition and an explosion of the gasolene takes place only at alternate revolutions of the crank-shaft.

Referring to the drawings, A represents the bed of the engine; B, its cylinder; C C, the fly-wheels, and C' the crank-shaft upon which the fly-wheels are mounted.

D D are the cranks, and D' the piston-rod, connecting the cranks with the piston.

E is the igniting-chamber, located at one side of the cylinder, and F is the exhaust-chamber at the other side. These communicate with the interior of the cylinder through ports e and f, respectively. The valve E' in chamber E controls the admission of the oil, and the valve F' in chamber F controls the exhaust. The passage E² admits oil to valve E', and the passage F² below the exhaust-valve is the exit-passage for the products of combustion.

The oil is fed by the following means: A pipe G is connected with a source of oil-supply and leads to a pump G', which is operated by an elbow-lever G², pivoted at G³ and having its horizontal arm connected to the stem of the pump-piston by a link G⁴. The lever is actuated in one direction by the contact of its vertical arm with the eccentric G⁵ upon the crank-shaft C' and in the other di-

rection by the spring G⁶, joined to the horizontal arm of the lever. The pump forces the oil through the pipe G⁷ into the overflow-chamber H. The latter connects with the oil-feed pipe G⁷ and with the overflow-pipe H⁵, leading back to the source of supply. The oil moves from chamber H to a nozzle H⁹, horizontally arranged, as shown, and extending into the elbow H¹², which is joined to pipe E² and connects the same with the air-pipe H¹¹, by which the necessary air is admitted to pipe E², where it may intermingle with the oil.

In the igniting-chamber is located the sparking-contacts, one of which may be a spring and is shown at J². It is mounted on the inner end of a binding-post J⁶, insulated at J⁴ and J⁵. The vibrating contact (not shown) is supported on shaft J⁷, actuated by rod J⁸, having a strap J⁹ passed around the eccentric G⁵, this connection being established by the arm J¹⁰ on shaft J⁷ and extending over rod J⁸ and caused to move with the rod by means of the spring shown and the arm J¹³, carried by a sleeve J¹⁴, loose upon the rod. The arm J¹³ bears against one side of arm J¹⁰ and the spring against the opposite side thereof.

For the purpose of starting the engine I provide the following means: A pipe K, having an upturned open end K' and connected with a hand-pump K² and also having a check-valve K³, extends up to and enters the side of the igniting-chamber at K⁴, as shown at Fig. 1. A small amount of oil is poured in at the open end K', the controlling-valve K⁵ opened; and the hand-pump is then operated and acts to open the check-valve and to draw the oil in K', accompanied with air, and force it up into the igniting-chamber. The arm J¹⁰ on the sparker-shaft is then temporarily released from the rod J⁸ by turning the sleeve J¹⁴ from its working position, which is shown at Fig. 6, to the position of Figs. 1 and 2, this movement of the sleeve carrying the arm J¹³ away from engagement with the arm J¹⁰. The arm J¹⁰ will now be free to be oscillated by hand, and such oscillation will cause a spark, and as soon as the explosion has taken place the engine will start and draw its supply of fuel from the pump G', and the valve K⁵ in the pipe K should then be closed and the sleeve

turned back, so as to cause reengagement of the arm J^{10} .

In the ordinary operation of the engine the charges of oil and air will be drawn in past the valve E' by the suction created by the piston; but I prefer to provide means whereby said valve may be yieldingly held to its seat, so as to prevent the entrance of fresh charges. These means are thrown into operation by the engine-governor whenever the speed becomes greater than is desired.

The governor comprises two swinging balls L fast upon a shaft L' , which receives motion through gears L^2 , L^3 , and L^4 from the main shaft. L^5 are springs bearing upon the swinging balls and tending to keep them close to the axis, and these springs are secured to a sleeve L^6 , sliding upon the shaft L' . When the balls throw out, they force the sleeve against the end of and actuate a horizontally-vibrating lever L^7 , pivoted at L^8 and joined at its farther end to the eye L^9 of a rod L^{10} , carrying upon its farther end a notched block L^{11} . This rod is arranged transversely of the engine, as plainly seen more particularly at Figs. 4 and 5. The lever L^7 is returned to its normal position by a spring L^{12} , held stationary at one end by a screw L^{13} and bearing at its other end upon the lever, as shown at Fig. 9, and the end of the rod L^{10} to which the block is attached is supported upon a projection L^{14} , formed upon the bracket L^{15} . Upon one side of the gear L^8 is a cam M , (seen at Fig. 3,) and this cam, which is geared to revolve only once to two revolutions of the main shaft, acts upon the end of a lever made in two parts M' and M^2 , both pivoted at M^3 and locked together, so the part M' may control the part M^2 in one direction by means of a pin M^a on the former projecting over the latter. The part M^2 is provided with a knife-edge projection M^4 , adapted to engage the notch of the block L^{11} . The part M' is held up against the cam by the spring M^5 . The main purpose of this two-part lever is to operate the exhaust-valve F' , as will be mentioned later on; but it also serves as the means for yieldingly holding valve E' to its seat through the medium of the sliding block M^6 , already described, and a lever M^7 , pivoted at M^8 and having in one end a set-screw M^9 , bearing upon the top of the part M^2 of the two-part lever, and also having a spring extension M^9 , joined to the stem of valve E' . The operation of these parts, briefly, is as follows: When the governor-balls open beyond the extent caused by the normal speed of the engine, they force lever L^7 in the direction which causes the rod L^9 to move the block L^{11} directly under the knife-edge M^4 , thereby holding the part M^2 of the two-part lever up, so that it cannot move down any farther than is permitted by the engagement of the knife-edge with the block. The two parts of the lever are joined in such manner as to permit this holding up of the part M^2 independently, and it results in the retaining of the valve

E' upon its seat, because the lever M^6 is thereby held in the position in which its spring-arm will act downwardly upon the valve-stem, and the valve being thus detained on its seat no fresh charges are admitted, and in consequence the engine soon slows down, and the closing of the governor-balls allows the spring L^{12} to return lever L^7 to its normal position, which causes the shifting of block L^{11} away from the part lever M^2 and allows the latter to resume its vertical movements with the part M' . The lever M^2 when locked in its upper position by the block L^{11} also acts to hold the exhaust-valve F' open at the same time the valve E' is closed. This is due to the extension of the stem F^3 of said valve F' down to a bearing on the lever M^2 , as seen at Figs. 1 and 3, and in consequence of the holding open of the exhaust-valve in this manner it will be seen that there will be no danger of the suction on the inlet-valve overcoming the power of spring M^9 . The spring F^4 , surrounding the stem F^3 , acts to retain the exhaust-valve in its closed position, except when overcome by the lever M^2 at the proper times for giving egress to the products of combustion, and it also acts incidentally to return lever M^2 after its upward movements.

For stopping the engine I employ the device shown at Fig. 3, consisting of a vertical lever N , freely pivoted to the bed at N' and having at its upper end a pivoted weight N^2 , controlling the lever. At its lower end the lever is positioned between two guide-pins N^3 and N^4 , secured in part lever M' , and at said end it is also provided with a projection N^5 . In the position shown the weight inclines in the direction which throws the lever against the pin N^4 , this being the position occupied while the engine is running; but if the weight be thrown over so as to incline in the opposite direction the bottom of the lever will be moved against the pin N^3 , and in this position at the first downward movement of lever M' the projection N^5 will set over and engage said pin and lock the lever in its lower position, and this results in the holding of the part lever M^2 in its upper position, with the inlet-valve closed and the exhaust open. It will thus be seen that the engineer has only to reverse the weight N^2 from the position illustrated to stop the engine. This optional mechanism for controlling the valves is also useful in starting the engine, as it enables the operator to turn the fly-wheel by hand without causing any compression in the cylinder.

The electric circuit used for causing the ignition of the vapor is established just before and broken just after each ignition, so that no waste of battery-power will occur at the contacts taking place between the sparking devices during the intervals between the ignitions. In order to accomplish this result, the wire from one side of the battery is connected to the bolt-head J^6 , and the one from the other side is joined to a spring-con-

tact O, supported upon but insulated from the stationary part of the engine in such position that one of its ends will bear upon the point of cam M as the latter passes. 5 While this contact of the cam continues, the current is established from the cam through the intervening parts of the engine to the movable sparker, but will be broken as soon as the cam has passed out from the contact. 10 Of course it will be understood that the circuit will be established in this manner whenever the charge of vapor in the cylinder is ready for ignition and broken immediately after the ignition, so that no current will be 15 on during the ensuing three contacts between the sparking devices.

When the engine is running, the cam M through the medium of the two-part lever M' M² lifts the valve F' at the proper times to 20 give escape to the products of the explosions, the closing of said valve being brought about by the spring F⁴.

In addition to the other objects attained by making the exhaust-lever M' M² in two parts 25 is the avoidance of the noise which occurs when integral levers are used by reason of the contact therewith of the cam. With the two-part lever it becomes possible to keep the roller on the part M' of the lever in constant 30 bearing with the cam while the part M² is locked, thereby preventing all noise at the cam and causing only a slight click at the pin M^a. The adjusting-screw M⁸ serves not only to regulate the tension of the spring M⁹, but 35 also to regulate the extent of opening of the intake-valve.

I claim—

1. The combination of the governor with the intake and exhaust valves, and the two- 40 part lever, the governor controlling said lever and preventing it from opening the exhaust-valve and also acting to hold the intake-valve closed, substantially as specified.

2. The combination with the intake and 45 exhaust valves of a vapor-engine, of a two-part lever M' M², the cam actuating said lever, the governor, and means whereby the governor may cause said lever to hold said valves against operating, substantially as 50 specified.

3. The combination with the intake and exhaust valves of a vapor-engine, of a two-part lever M' M², the cam actuating said lever, the governor, and means whereby the 55 governor may cause said lever to hold the intake-valve closed and the exhaust-valve open, substantially as specified.

4. The combination with an intake-valve, of a pivoted lever M⁶ having a spring extension connecting it to the valve, an adjusting device for regulating the tension of the spring and the throw of the valve, a lever M² for locking the lever M⁶, the governor, and means having no connection with the exhaust-valve

whereby the governor causes the locking action by lever M², substantially as specified. 65

5. The combination with the intake-valve and the pivoted lever M⁶ having a spring extension connecting it to the valve, of the two-part lever, one part of which is adapted to 70 lock said lever M⁶, the governor, and connections between the governor and the two-part lever, whereby the latter is made to lock lever M⁶, substantially as specified.

6. The combination with the governor and 75 exhaust-valve, of a two-part lever and cam for opening said valve, and mechanical connections whereby the governor locks one part of said lever against action, substantially as specified. 80

7. The vapor-engine wherein are combined an exhaust-valve and a lever for opening the same, said lever being made in two parts, and the part joined to the valve being adapted to be locked stationary, substantially as specified. 85

8. The vapor-engine wherein are combined an exhaust-valve and a lever for opening the same, said lever being made in two parts, both pivoted at the same point and one part 90 actuating the other in one direction, and means for locking the part thus actuated, substantially as specified.

9. The combination with the exhaust-valve lever, made in two parts M' and M² as set 95 forth, of means for locking the part M' down, thereby causing the retention of the valve in its open position, substantially as specified.

10. The combination with the exhaust-valve and its pivoted operating-lever, the latter 100 made in two parts M' and M², of means operable at will acting to lock the part M' in its lower position and thereby to raise the part M² to its upper position and holding the valve open, substantially as specified. 105

11. In a gasolene-engine, the intake and exhaust valves and the two-part lever connected to both valves, in combination with a lever N locking one part of said lever, and a weighted handle N² controlling said lever N, 110 substantially as specified.

12. In a gasolene-engine, the intake and exhaust valves, and their operating mechanism, the latter embracing a two-part lever, in combination with a controlling-lever N operable at will and having a pivoted weight N², 115 substantially as specified.

13. In a gasolene-engine, the combination with the intake and exhaust valves and their operating mechanism, of a hand-lever N for 120 controlling said operating mechanism, said lever having two positions and also having a pivoted and weighted handle for retaining it in said positions, substantially as specified.

JOSEPH B. RODGER.
